UNITED STATES PATENT OFFICE.

OSCAR S. HUMMEL, OF SAN DIEGO, CALIFORNIA.

DESIGN FOR A PIANO-CASE.

41,222.

Specification for Design.

Patented Mar. 7, 1911.

Application filed January 13, 1911. Serial No. 602,523. Term of patent 3½ years.

To all whom it may concern:

Be it known that I, OSCAR S. HUMMEL, a citizen of the United States, residing at San Diego, in the county of San Diego and State of California, have invented a new, original, and ornamental Design for Piano-Cases, of which the following is a specification, reference being had to the accompanying drawing, forming a part thereof.

The figure is a perspective view of a piano case showing my new design.

I claim.

The ornamental design for a piano case as shown.

In testimony whereof I affix my signature in presence of two witnesses.

OSCAR S. HUMMEL.

Witnesses:

J. W. MASTER,
F. M. KEENEY.

Copies of this design may be obtained for five cents each, by addressing the "Commissioner of Patents, Washington, D. C."
